UNITED STATES PATENT OFFICE.

CLARK S. WEISS, OF BELLEVILLE, NEW JERSEY.

GASOLENE-SEPARATOR.

1,063,754.

Specification of Letters Patent.

Patented June 3, 1913.

Application filed February 7, 1913. Serial No. 746,792.

To all whom it may concern:

Be it known that I, CLARK S. WEISS, a citizen of the United States, and a resident of Belleville, in the county of Essex and State of New Jersey, have invented a new and Improved Gasolene-Separator, of which the following is a full, clear, and exact description.

The invention relates to gasolene separators in which the separation is gravitational, and has reference more particularly to a device comprising a funnel having a segmental diaphragm and a plurality of valve-controlled outlets all below the diaphragm.

The object of the invention is to provide a single inexpensive and efficient gasolene separator by means of which the water and the sediment present are prevented from overflowing in lieu of the gasolene, and in which all of the gasolene can be substantially drawn off without drawing off the sediment or the water, and which can be easily cleaned of the sediment and water present in the separator.

Reference is to be had to the accompanying drawings forming a part of this specification, in which the same characters of reference indicate the same parts in both the views.

Figure 1 is a plan view of the funnel proper; and Fig. 2 is an elevated section of a separator embodying my invention.

Referring to the drawings, 5 represents a gasolene tank of any suitable form provided with an opening 6. Attached to the tank axially with the orifice is a funnel 7 provided with a flange 8 which contacts with the bottom of the tank 5 and is connected to the tank by means of rivets 9, or any other suitable means. The funnel 7 is also provided with a semi-circular diaphragm 10 preferably in the same plane with the flange 8 and substantially normal to the axis of the funnel.

The free end 11 of the diaphragm 10 is bent downwardly toward the converging portion of the funnel. The lowermost portion of the funnel 7 is provided with a nipple 12 rigidly secured to the inner side of the funnel and carrying a draining cock 13. Directly under the diaphragm 10 substantially on a line normal to the edge 11 of the same is a nipple 14 rigidly secured to the sides of the funnel 7. Intermediate the

nipple 12 and nipple 14 a tubular member 15 is rigidly secured to the side of the funnel 7, lying substantially in the same plane with the nipples 12 and 14. The tubular member 15 has interiorly of the funnel a curved projecting portion 16 passing through the curved end 11 of the diaphragm 10 and above the same into the tank 5, the portion 16 being substantially axial with the funnel. The exterior projecting end 17 of the tubular member 15 is substantially parallel to the nipple 14. The end 17 and also the nipple 14 are each provided with cocks 18 and 19, respectively. A pipe 20 is leading from the cock 18 to any desired place, and a connection 21 is formed from the cock 19 to the pipe 20.

The operation of my device is as follows: When the gasolene in the tank is in abundance the sediment and water necessarily will settle in the lower portion of the funnel, as indicated in Fig. 2 by heavy broken lines and spotting the same. The gasolene is then drawn off by means of the tubular member 15 through the cock 18. When the gasolene level in the tank has reached the stage as indicated in Fig. 2, no gasolene will be supplied then by means of the tubular member 15, and the cock 18 is then closed and the cock 19 opened. Gasolene then will flow through the nipple 14, cock 19, tubular connection 21 and to the pipe 20. The reason for forming the diaphragm as described is to prevent the sediment and water when flowing into the funnel from entering the nipple 14, and also when the gasolene is drawn through the nipple 14, as above described, the sediment or water disturbed by the flow will not pass near to the nipple 14 but exactly at the opposite end of it. This structure gives a perfect separation of gasolene from the water and other matter present in the gasolene. The cleaning of the separator is done by simply opening the cock 13 and thereby draining off the sediment and water present in the lower portion of the funnel. It can be easily seen that the bottom of the tank and separator can be formed integrally or separate; in either case the segmental diaphragm will form part of the bottom.

Having thus described my invention, I claim as new and desire to secure by Letters Patent:

1. In a gasolene separator, a funnel, a seg-

110

mental diaphragm projecting from one side of said funnel substantially normal to the axis of the funnel, three alining outlets from said funnel substantially central with said diaphragm and all below the same, and valves for each of said outlets, the intermediate of said outlets having an interior tubular portion leading through and above said diaphragm, and said higher outlet being connected to said intermediate outlet at the exterior of said funnel:

2. In a gasoline separator, a funnel having a flange at the largest portion thereof and a segmental diaphragm lying in the same plane with said flange and extending past the axis of said funnel, said diaphragm having its free end turned toward the converging portion of the funnel, a valve-controlled outlet in the lower portion of said funnel, a valve-controlled outlet directly under said diaphragm substantially central with said diaphragm, and a valve-controlled outlet intermediate said outlets having a tubular portion in said funnel projecting through the curved end of said diaphragm and above the same and lying substantially in the axis of the funnel, said outlet under said diaphragm and said intermediate outlet being connected with each other.
3. In a gasoline separator, a funnel having a segmental diaphragm projecting from one side of the funnel and substantially normal to the axis of the funnel, and a plurality of valve-controlled outlets from said funnel, all below said diaphragm and all at different levels one of said outlets having a

tubular extension projecting above said diaphragm.

4. In a gasoline separator, a funnel, a substantially semi-circular diaphragm in said funnel normal to the axis of the funnel, a plurality of outlets from said funnel, each at a different level and all below said diaphragm, and valves for controlling each of said outlets, and one of said outlets having an interior tubular extension projecting through said diaphragm and above the same.

5. In a gasoline separator, a funnel having a segmental diaphragm projecting from one side substantially normal to the axis and having its straight edge curved toward the converging portion of the funnel, a plurality of outlets from said funnel, each at a different level, all in alinement and substantially normal to the said edge of said diaphragm and all below the same, and a valve for controlling each of said outlets, one of said outlets having a tubular portion within said funnel leading through said curved edge of said diaphragm and above the same, said outlet having the said tubular portion being connected to the outlet above, exterior of the funnel and of their valves.

In testimony whereof I have signed my name to this specification in the presence of two subscribing witnesses.

CLARK S. WEISS.
